ATTORNEY

UNITED STATES PATENT OFFICE.

JOSEPH F. DESEMO, OF COFFEYVILLE, KANSAS.

MAGAZINE PENCIL.

Application filed October 30, 1926. Serial No. 145,180.

My invention relates to magazine instruments for marking purposes, and more particularly to a mechanical pencil that is adapted to carry leads of different kinds and selectively place them in writing position.

The object of my invention is to provide a mechanical instrument having a plurality of means for carrying a plurality of marking substances of different kinds, means for selecting any desired one of said kinds of substances, means for placing said selected substances in marking position, and means for securing the unselected substances at rest. Specifically my device in its preferred and illustrated form comprises a barrel enclosing a rotatable cylinder and guiding means, a rotatable screw shaft on which a traveler functions as holder and propeller therein, carriers co-operating with said guiding means, each 15 of said carriers being adapted to carry a lead and each of said carriers being adapted to be moved by said traveler out of retracted position into alignment with an opening and toward said opening to project the lead carried 20 thereby through the opening into functional position. The arrangement of parts is preferably such that the rotatable cylinder is held against rotation when one of the leads is in functional position.

Other objects and advantages of the specific form of the invention illustrated will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would follow 35 within the scope of the claims. For example, the device may be adapted for the carrying of cylinders containing different kinds of fluids, such minor details being additionally provided as would accommodate the structure to the handling of the non-solid marking substance.

In the drawings:

Fig. 1 is a longitudinal fragmentary sectional view of a pencil.

Fig. 2 is a similar view but with one of the writing elements in functional position.

Fig. 3 is a fragmentary perspective view of the guide cylinder that supports the lead carriers.

Fig. 4 is a perspective view of the pencil

in which the manner of manually operating the selective mechanism is illustrated.

Fig. 5 is a cross sectional view on the line 5—5 of Fig. 1.

Fig. 6 is a cross sectional view on the line 60 6—6 of Fig. 1.

Fig. 7 is a cross sectional view on the line 7—7 of Fig. 1.

Fig. 8 is a longitudinal sectional view of one of the lead carriers.

Fig. 9 is a perspective view of the lead selecting and projecting mechanism, the parts thereof being shown separated.

Fig. 10 is a cross sectional view of the top and eraser parts of the pencil on the line 70 10—10 of Fig. 1.

Referring in detail to the drawings:

1 designates the barrel of the pencil, having an open upper end 2 and being provided near the upper end with openings 3 and window 4, 75 the lower end 5 being externally screw threaded for engagement with tip 6 which serves as the writing end of the pencil. The tip 6 is provided with the bore 7, the bottom wall 8 of which has a tapered circular throat 9 adjacent its periphery, the tip having a channel 10 associated with said throat. The bottom wall 8 of bore 7 is provided with a recess 11 axially disposed thereto for a purpose later to be described.

The open upper end 2 of the barrel 1 is provided with a cap 12 detachably engaged therewith and having internal longitudinal recesses 13 for engagement of the cap with holder 14 having internal ribs 15 for securing an eraser 16 within said holder, the holder 14 having further details to be later described.

A disc-like bearing member 17 is removably positioned in the tip 6 closing the lower end of the barrel and resting upon the bottom wall 8 of tip bore 7, said disc-like bearing member 17 having a depending lug 18 adjacent to its periphery and projectible into the throat 9 of said bottom wall, the lug having an orifice 19 coinciding with the lead channel 10 of tip 6; the disc 17 has projections 20 on its surface and a central opening 21 axially coincident with recess 11 in bottom wall 8 of bore 7, and of less diameter than the same.

A shaft 22 is provided having a reduced lower extremity 23 projecting into recess 11 of the tip and rotatably mounted in the opening 21 of the disc bearing member 17, a bolt and washer element 24 serving to engage the shaft with the disc bearing member. The 110

- shaft 22 is provided for part of its length with an external screw thread of coarse pitch 25 whereby the said shaft so rotatably erected is constituted a perpetual screw or worm. 5 The shaft 22 has an upper unthreaded portion 26 and terminates upwardly in a squared end portion 27 which is removably engaged with the interiorly squared downward projection 28 of the eraser holder 14, said engagement providing that the rotation of eraser holder 14 causes the equal and simultaneous rotation of the perpetual screw shaft 22.
- Associated with the upper portions 26 and 15 27 of the shaft 22 is a spool-like member 29 comprising a tubular body 30, an upper flange 31 of such diameter as to contact the inner side of the wall of the barrel 1, and a lower flange 32 of less diameter than said upper flange, the spool-like member 29 being mounted on the upper unthreaded portion of shaft 22, and the upper squared end of said shaft projecting beyond said spool-like member into engagement with the squared end of 20 eraser holder 14, the eraser holder being therefore rotatably seated on the upper surface of said spool-like member. The spool-like member is secured at a desired position within the barrel to the wall thereof, so constituting a bearing member for shaft 22 journaled therein by construction indicated, by 25 means of fingers 33 having slots 34 engaged with the upper flange 31 of said spool-like member by pins 35, the pins having heads 36, said heads projecting into the slots 34, the fingers being transversely slidably, because of the provision of the pin-and-slot arrangement, into engagement with the barrel 1 by 30 projection of the same into the barrel wall, the barrel having recesses 37 for the reception of the projected fingers.
- The spool-like member is thus secured in the barrel as a bearing member for the shaft and for the eraser holder, and also is secured 45 against rotation. The lower flange 32 of spool-like member 29 is provided with aperture 38, has a sector cut away whereby a notch is produced as indicated at 39, and has a slightly beveled upper surface 40, all for purposes later to be described.
- Mounted rotatably within the barrel 1 and on the disc-like bearing member 17 and spaced from the under side of upper flange 31 of the spool-like member 29 as indicated at 41, is a 50 guide bundle 42 illustrated in Fig. 3, comprising a cylindrical upper portion 43, a cylindrical lower portion 44 and an intermediate portion consisting of guides 45. The upper portion 43 has a longitudinal dimension greater than the longitudinal measure of 55 openings 3 and window 4 of the barrel, and is adapted for co-operation therewith, indicia 46, such as the description of colors, being positioned on said upper portion 43 for single and successive visibility through window 4, and
- parts of the surface of said upper portion being exposed through openings 3 for frictional contact of agencies inserted into said openings as will later be described. The lower portion 44 of said guide bundle is provided with 60 notches 47 having curved edges, adapted for the engagement of projections 20 of the disc-like bearing member 17 with said lower portion 44, whereby the guide bundle is detachably latched with the bearing member against 65 accidental rotation; the mutual operation of said projections and said notched lower portion of the guide bundle 42 providing step by step rotation of the guide bundle as will appear. It should be noted that the altitude of 70 said projections 20 is less than the distance by which the upper portion 43 of the guide bundle 42 is spaced as indicated at 41 in Figs. 1 and 2 from the upper flange 31 of the spool-like member 29, for purposes associated with 75 the rotation of the guide bundle.
- The guides 45 constituting the intermediate portion of guide bundle 42 are tube-like members preferably struck inwardly and longitudinally on a cylinder from which the guide 80 bundle may be constructed and arranged in a circular series being preferably equi-distantly spaced, the interior free edges of each instriuk tube-like guide being spaced to form slots 48 extending longitudinally of the 85 guides and of the guide bundle.
- The guides, as may be observed in Fig. 3, are by uniformity of construction equally spaced from the axis of the guide bundle; and their inner edges are adjacent to but 90 spaced from a cylinder erected on and extended from the periphery of the lower flange 32 of spool-like member 29 and parallel with the shaft 22. The guides 45 being by construction interjected into the body of the 95 guide bundle 42, form interior shoulders therein such as the shoulders 49 at the upper ends of the guides 45 as indicated by the dotted lines in Fig. 3.
- Slidably mounted in guides 45 and removable through the open ends thereof are lead carriers 50 shown in detail in Fig. 8 having lugs 51 projecting through the slots of said guides, the lead carriers preferably having closed upper end walls 52 and open lower 100 ends 53, and having longitudinal slots 54 extending from said lower ends a part of the distance to the said closed ends. Leads 55 are provided to be carried by said lead carriers, the end of a lead being embraced by 105 the slotted end of a lead carrier, such slotted end being preferably deformed to tightly grip the carried lead.
- The rotatable guide bundle 42 is held yieldingly and controllably in engagement with 110 the disc-like bearing 17 by means now to be described.
- A washer 56 is provided slidably positioned on the tubular body 30 of the spool-like member 29 and between the upper flange 31 and 115

the lower flange 32 thereof; said washer being adapted to slidable positioning in the upper cylindrical portion 43 of guide bundle 42, and seated on the shoulders 49 of guides 45. A compression spring 57 is provided, positioned interiorly of said upper cylindrical portion 43, based against the upper flange 31 which has been described as removably secured to the barrel against vertical movement and against rotation. The spring exerting its influence against the washer 56, the influence being transmitted to the guide bundle, thus holds the guide bundle in engagement with the disc-like bearing 17 yieldingly. Operating means, for example the fingers, may be inserted through the openings 3 of the barrel, there contacting the surface of the upper portion 43 of the rotatable guide bundle; the fingers may exert a complex of pressures adapted to rotate the guide bundle. The guide bundle, rotating, releases its notches 47 from engagement with the projections 20, laterally and perpendicularly withdrawing the notches therefrom, the process being facilitated by the structure described, the notches having curved edges. The guide bundle is permitted to advance vertically while rotating because of the spaced relation indicated at 41 with the bearing flange 31; and the spring, the influence of which was purposefully opposed, tending to restore the guide bundle to engagement with the bearing 17 upon cessation of such opposing influence and upon coincidence of said notches 47 with projections 20, and to maintain such engagement against accidental disturbance.

A traveler 58 constituting a lead projecting member is mounted on shaft 22, the traveler having a cylinder-like body portion 59 internally screw threaded with threads of the same pitch as the threads on the shaft 22 and an arm 60 extending endwise from said body portion and projecting laterally therefrom; the arm 60 having a mouth 61, said arm being adapted to enter the notch 39 in the lower flange 32 of spool-like member 29, and the said mouth comprising paired lips 62 below and 63 above, being adapted to engage the lugs 51 on the lead carrier 50. Body portion 59 is provided with longitudinal rib 64 having a bore 65, the axis of said bore being preferably diametrically opposite the said arm 60 extending from said body as described. The lower flange 32 of spool-like member 22 is provided with an opening 38 being diametrically opposite the notch 39 of said lower flange 32, the bore 65 and the opening 38 being spaced equally from the common axis of the body portion 59 and of the spool-like member 29.

A rod 66 is provided, the chief function of which is to retain the traveler 58 from rotation on the shaft 22, the rod projecting through the bore 65 of the traveler's flange

64, and through the opening 38 of the lower flange 30 of the spool-like member 29, the disc-like bearing member having opening 67, and the lower end of said rod 66 projecting into said opening, the rod thus being anchored by engagement with said disc-like member and said spool-like member 29, the washer 56 being preferably provided with an opening whereby the rod may be permitted to project upwardly toward and against the upper flange 31 of the spool-like member by passage through said opening 68 of said washer 56.

Assuming the parts described to be assembled, each lead carrier having a lead, each lead carrier being positioned in a guide, the guide bundle fixed against accidental rotation by engagement of its lower portion with the projections of the disc-like bearing, the spring 57 tending to retain the guide bundle in engagement with the disc-like bearing member, the traveler mounted on the perpetual screw shaft and screw-movable only, it is now necessary to describe other features of the assembly, and then to refer to operation.

The lead carriers 50 are free to slide in guides 45; considering the guide bundle 42 as segregated from the pencil. When the guide bundle becomes associated with the other parts of the pencil, however, the lead carriers, as can be best observed in Fig. 2, are retained adjacent the upper portions of the guide bundle, by the co-operation of the lugs on the lead carriers with the lower flange of the spool-like member; the lead carriers being held thus suspended and in such spaced relation vertically that the depending leads 55 may possess maximum length proportionate to the predetermined dimensions of the barrel, the leads being spaced from the disc-like bearing member 17.

The lead carriers, therefore, are retained adjacent to the upper portion of the guide bundle, by the bearing of their lugs on the flange 32 that projects downward among the guides 45, the extent of such projection being well shown in Fig. 2 and being measured by the distance between the washer 56 seated on the upper shoulders 49 of guides 45 and the flange 32.

A difference between Fig. 1 and Fig. 2 is that Fig. 1 shows all the lead carriers 50 in retracted position, and equally spaced from the shoulders of the guides, while Fig. 2 shows one of the lead carriers in segregated position, being advanced downwardly to project the lead into functional position in the tip of the pencil. In Fig. 1, one lead carrier is shown positioned adjacent to the notch 39 in flange 32, the lug of the carrier being engaged by the mouth 61 of the traveler 58, the arm 60 of the traveler being projected into said notch.

The upper face of the lower flange normally supports the lead carriers at rest by

means of the lugs on the same. The arrangement of parts is such that when the rotatable guide bundle 42 is fixed against rotation by engagement with the projections on the 5 disc-like bearing member 17, one of the lead carriers is aligned with the notch 39, the notch is aligned with the point opening 10 in the pencil tip 6; the arm 60 of the traveler 58 being also in the same alignment. Another coinciding element entering the relations just outlined is the indicia 46, one of which, corresponding to and indicating one of the leads 55, appears at the window 4 of barrel 1 while the alignment prevails of indicated corresponding lead in its carrier with traveler arm 60 and notch 3 and of these with the point opening 10 in the tip 6. The rotation of guide bundle 42 brings about the positioning of the selected lead, the rotating 20 guide bundle causing the lead carrier to circulate peripherally of the spool-like member, the lugs of the lead carriers bearing on the upper surface of the lower flange of said spool-like member, the lugs in their circulation passing through the interposed mouth 61 of the traveler arm 60 projected into notch 39, the lower lip 62 of said traveler arm serving as a bridge to prevent the downward passage of lugs through notch 39, a carrier being aligned in the notch when selection occurs, the mouth 61 engaging the lug of said carrier.

The lead desired being selected and positioned in alignment with the tip opening, and 35 engaged with the traveler, is projected to and partly through said tip opening by the action of the traveler under the influence of the perpetual screw shaft 22 as rotated by the rotation of the eraser holder 14, shaft and holder being connected by squared members as described, or by rotation of the cap anchored on said eraser holder to produce co-operation in rotation.

The lead may be retracted from functional 45 position by reversal of direction of rotation of eraser holder whereby the screw thread 25 on the shaft 22 lifts the traveler and the traveler lifts the lead carrier to the normal spaced position from the top of the guide bundle, in 50 which position the traveler arm is in the notch arranged for release of the raised carrier and reception of another.

The pencil may be supplied with leads by insertion of leads through the tip channel 10 55 and into successively projected lead carriers. The pencil may be disassembled by the withdrawal of the eraser holder from engagement with the squared end of the screw shaft, the withdrawal of fingers 33 thus exposed from 60 engagement in recesses 37 of the barrel, and the lifting of the guide bundle from the barrel by means of the shaft 22 the upper and lower bearings of which bear against the opposite ends of the guide bundle; the parts be-

ing then separated, carriers filled, carriers withdrawn from guides if desired.

What I claim and desire to secure by Letters-Patent is:—

1. In a mechanical pencil, a barrel, a cylindrical member rotatable in the barrel, said 70 rotatable member having a plurality of guides therein, a lead carrier mounted in each of said guides for movement longitudinally therein, a member supporting a plurality of said carriers in retracted position in said guides, a 75 rotatable shaft in the barrel co-axial therewith, a longitudinally movable feeding member mounted on the shaft and movable thereby longitudinally thereof for moving a selected carrier lengthwise of its guide out of 80 and into retracted position, and means to hold said rotatable member against rotation.

2. In a mechanical pencil, a barrel, a rotatable member having a plurality of guides therein, a lead carrier mounted in each of said 85 guides for movement longitudinally therein, a member supporting a plurality of said carriers in retracted position in said guides, a shaft rotatable in the barrel and co-axial therewith, a feeding member mounted on the 90 shaft and movable thereby longitudinally therewith for moving with a selected carrier while moving said carrier lengthwise of its guide out of and into retracted position, means for confining said feeding member to a 95 longitudinal course in the pencil including a rod fixed in the barrel, and means to hold said rotatable member against rotation.

3. In a mechanical pencil, a barrel, a rotatable member having a plurality of slotted 100 guides therein, a lead carrier mounted in each of said guides for movement longitudinally therein, and provided with a lug extending through the slot of its guide, a notched member adapted for the passage therethrough of 105 the carrier lugs supporting a plurality of said carriers in retracted position in said guides, a shaft rotatable in the barrel and co-axial therewith, and means mounted on the 110 shaft and movable thereby into the supporting member notch for engaging a carrier lug for moving one of said carriers lengthwise of its guide out of and into retracted position, said supporting member and said means cooperating to select a predetermined one of 115 said carriers for movement out of retracted position upon rotation of said rotatable member into a predetermined position.

4. In a mechanical pencil, a rotatable member having a plurality of guides therein, a lead carrier mounted in each of said guides for movement longitudinally therein, each carrier having a projection, a member supporting a plurality of said carriers in retracted position in said guides and means including a shaft coaxial with the rotatable member for moving one of said carriers lengthwise of its guide into and out of retracted 120 125

position, said supporting member having a gap therein and said means having a pair of spaced projections thereon adapted to enter said gap and engage with a projection on any one of said carriers to move the same out of retracted position.

5. In a mechanical pencil, a rotatable member having a plurality of guides therein, a lead carrier mounted in each of said guides for movement longitudinally therein, a member supporting a plurality of said carriers in retracted position in said guides, means for disengaging a selected carrier from the support, and means including a rotatable shaft for engaging one of said carriers and moving said engaged carrier lengthwise of its guide out of retracted position, said supporting member and said means co-operating to return a carrier to retracted position and in engagement with said supporting member.

6. In a mechanical pencil, a rotatable member having a plurality of guides therein, a lead carrier mounted in each of said guides for movement longitudinally therein, a member supporting a plurality of said carriers in retracted position in said guides, means for disengaging a selected carrier from the supporting member, including means for moving said selected carrier lengthwise of its guide out of retracted position, said disengaging means including a shaft and a member movable on the shaft and being adapted to return a carrier to retracted position, the selected carrier being moved into engagement with said supporting member upon rotation of said rotatable member, said rotation releasing the carrier from the moving means.

7. In a magazine pencil, a barrel, a tip member engaged with the barrel having a lead passage parallel with the axis of the barrel and offset therefrom, a shaft extending axially of the barrel and rotatable therein, lead carriers movably supported within the barrel, means for aligning a selected car-

rier with the passage including means for removing the selected carrier from the support, and means operable by the shaft for receiving a selected carrier and moving the same longitudinally in the guide member thereof for passing the lead through the passage.

8. In a magazine pencil, a barrel, a rotatable member having an axial shaft-end receiving recess and a lead passage parallel with the axis of the barrel and offset therefrom, said tip member having a disk-receiving portion, a disk fixed in the tip having guide member-engaging ribs on its upper face and an opening coinciding with said tip passage, a shaft extending axially of the barrel and rotatably supported by said disk, a rotatable lead carrier guide having a cylindrical portion provided with notches for engaging the disk ribs and a plurality of carrier-retaining members, lead carriers retained in said members, means supporting the lead carriers, and means including a member movable longitudinally of the barrel by the shaft for moving a carrier to pass a lead through said tip passage.

9. In a magazine pencil, a barrel, a shaft rotatable therein, a spool-like member having upper and lower disks removably engaged with the barrel, a collar slidable on said spool-like member between the disks, a coil spring urging said collar toward the lower end of the spool-like member, lead carriers annularly arranged in the barrel, means actuated by the shaft for moving the lead carriers longitudinally of the barrel, the lower end of said spool-like member being adapted to support the carriers, said spring-impelled collar being adapted to restrain the outward movement of the carriers yielding.

In testimony whereof I affix my signature.

JOSEPH F. DESEMO.
